DESIGN FOR A CARBURETOR OR SIMILAR ARTICLE

Arthur O. Randall, Miami, Fla., assignor to Randall Holding Corp., a corporation of Florida

Application February 21, 1935, Serial No. 55,556

Term of patent 14 years

To all whom it may concern:

Be it known that I, Arthur O. Randall, a citizen of the United States, residing at Miami, in the county of Dade and State of Florida, have invented a new, original, and ornamental Design for a Carburetor or Similar Article, of which the following is a specification, reference being had to the accompanying drawing, forming part thereof, and in which:

Figure 1 is a view in side elevation.

Fig. 2 is a top plan view.

Fig. 3 is a bottom plan view.

Fig. 4 is a view looking at the left hand side as illustrated in Figure 1.

Fig. 5 is a view looking at the right hand side as illustrated in Figure 1.

I claim:

The ornamental design for a carburetor or similar article, as shown.

ARTHUR O. RANDALL,
